PRESSURE OPERATED SWITCH

Application filed July 13, 1931. Serial No. 550,588.

This invention relates to a low pressure signal for automobile tires, the general object of the invention being to provide means for operating a signal when any one of the four tires of the vehicle becomes partly deflated.

This invention also consists in certain other features of construction and in the combination and arrangement of the several parts to be hereinafter fully described, illustrated in the accompanying drawings and specifically pointed out in the appended claim.

In describing the invention in detail, reference will be had to the accompanying drawings, wherein like reference characters denote like or corresponding parts throughout the several views, and in which:

Figure 1 is a fragmentary view with parts in section showing the invention applied to a wheel.

Figure 2 is a longitudinal sectional view of the pressure switch.

Figure 3 is a section on the line 3—3 of Figure 2.

Figure 4 is a section on the line 4—4 of Figure 2.

Figure 5 is a diagrammatic view of the circuit.

Figure 6 is a section on the line 6—6 of Fig. 1.

Figure 7 is an elevation of the part of the stationary portion of the brake drum.

In these drawings the numeral 1 indicates the stem of the innertube 2 of the tire 3, and the numeral 4 indicates the casing having one end formed with a threaded hole to receive the reduced end of the casing stem. Within the casing 4 is a member 5 for engaging the valve 6 of the stem to hold the same in open position when the casing is screwed on the stem.

The open end of the inflatable casing 7 formed of rubber or the like, is held against the outer end of the casing 4 by the nut 8 so that air from the tube 2 will enter the casing 7 to expand the same. A washer 9 is fastened to stem 10 which is slidably arranged in the non-conducting discs 11 carried by a tubular member 12 which is thread-

ed in the inner end of the casing 4 and acts as a closure member for the same.

A contact ring 13 is carried by one of the non-conducting discs 11 and is engaged by the head 14 on the stem 10 when the member 9 is moved toward the valve stem 1 by the spring 15 which has one end connected with the member 9 and the other end suitably connected with the nut. The contact 13 is connected by wire 15 to a cylinder 16 carried by and insulated from a stationary part 17 of the wheel and this cylinder has a carbon block 18 therein which is normally pressed outwardly by spring 19 in the cylinder so that the block will be held in engagement with a ring 20 in the brake drum 21 of the wheel and insulated therefrom by the non-conducting ring 22. A conductor 23 is connected with the ring 20 and to the circuit of the alarm A which includes the battery B.

It will of course be understood that one of these assemblies is placed on each wheel and the conductor 23 of each wheel is electrically connected with the alarm circuit as will be shown in Figure 5.

Thus it is seen that as long as the tires are fully inflated the inflatable member 7 will be expanded so that its pressure against the disc 9 will move the stem 10 and its head 14 to a position where said head will be out of contact with the member 13. Thus the circuit to the alarm will be broken. However as soon as one of the tires become partly deflated, the member 7 will partly contract and spring 15 will pull the member 9 and its stem 10 towards the valve stem so that the head 14 will engage the contact 13 thus completing the circuit to the alarm or signal A so as to notify the driver or other person in the vehicle that the tire is in need of air.

The alarm or signal A may be placed in any place desired such as on the instrument board or other part of the vehicle.

It is thought from the foregoing description that the advantages and novel features of the invention will be readily understood.

It is to be understood that changes may be made in the construction and in the combination and arrangement of the several parts

provided that such changes fall within the scope of the appended claim.

We claim:

5 In a low pressure signal for tires of motor vehicles, a casing having one end provided with a threaded hole, a second casing located in the first casing and having one end open, said end provided with an external flange, a nut threaded in the first casing and clamping the flange of the second casing against that end of the first casing which is provided with the threaded hole, the opposite end of the second casing being closed, a disk bearing against said closed end of the second casing, a contractable spring surrounding the second casing and placed in the first casing and having one end attached to the disk and the other to the nut, a stem connected to the disk and having a head on the free end, a hollow plug 10 closing the outer end of the first casing and having a partition therein formed of non-conducting material, a contact ring carried by the partition, the stem passing through the partition through the center of the ring, whereby when the inner casing contracts the head of the same will be engaged with the ring for closing a circuit.

15 In testimony whereof we affix our signatures.

20 JOSEPH G. GEWECKE.
MELVIN I. ELLISON.
WILLIAM H. MENKING.
